COMPOUND GRAVITY PRESSURE TANK

Christian Arne, Chicago, Ill., assignor to Chicago Bridge & Iron Company, a corporation of Illinois

Application March 12, 1949, Serial No. 81,032

4 Claims. (Cl. 137—208)

1

This invention relates to liquid storage systems and more particularly to compound gravity pressure systems for liquid storage tanks.

Liquid storage tanks, particularly water storage tanks, are often elevated in order to provide pressure throughout the supply system. Disregarding friction, which is a negligible factor in the ordinary storage tank, the pressure generated by the tank is a function of the hydrostatic head of liquid in the tank and in the riser connecting the tank with the system. Thus, in the ordinary construction it is necessary to double the height of the tank if twice the pressure is desired. Obviously, there is a practical limit to the extent to which water tanks may be elevated in order to increase the pressure in the system and therefore if further pressure is desired it has been the custom to supplement the pressure generated by gravity, that is, the hydrostatic pressure, by means of auxiliary devices such as pumps and the like.

I have invented and am herein disclosing and claiming a compound gravity pressure tank by means of which the hydrostatic pressure developed by a series of elevated tanks may be accumulated so as to generate a final pressure equal to that which would be generated by a single tank having an elevation equal to the sum of the elevations of each tank.

The invention will be described in conjunction with the accompanying drawings in which:

Fig. 1 is a vertical section through a series of elevated pressure tanks illustrating the principle of the invention;

Fig. 2 is a side elevation of a specific example of a compound gravity pressure tank embodying the invention;

Fig. 3 is a top plan view of the apparatus of Fig. 2; and

Fig. 4 is a vertical section through the compound gravity tank of Fig. 2.

Referring now to Fig. 1, I show a plurality of elevated tanks 10, 11, 12 and 13. Tank 10 may be open at its top, if desired, while tanks 11, 12 and 13 should be sealed, that is, should be closed vessels except for such openings as may be necessary to carry out the invention as will hereinafter be described.

A riser 14 connects the tank 10 with a sealed container 15 and extends below the level 16 of liquid in the container. The container 15 is sealed except for a header 17 which opens to the container above the level of the liquid and connects the container to the top of the tank 11. The pressure generated by the liquid at the tank

2

10 and riser 14 is thus transmitted by air in the container 15 and header 17 to tank 11. Tank 11 is connected by means of a riser 18 to a second container 19, the riser extending into the container 19 and below the level 20 of liquid therein. A second header 21 connects the space above the liquid in the container 19 with the top of tank 12 thereby subjecting the tank 12 to the pressure generated by the liquid in the tank 11 and riser 18 plus the pressure transmitted to the tank 11 through the header 17. The tank 12 is connected by means of a riser 22 to a third sealed container 23 and the riser 22 extends below the level 24 of liquid in the container 23. A third header 25 connects the space above the level of the liquid in the container 23 with the top of tank 13. A riser 26 establishes the connection between the tank 13 and the outlet 27 for the system which outlet may be used to fill the system at the start. The pressure at the outlet is equal to the sum of the hydrostatic pressures generated by each of the tanks 10, 11, 12 and 13 and the risers associated therewith, and is substantially equal to the pressure that would be generated by a single tank and riser elevated above the outlet a distance equal to the sum of the elevations of each of the tanks in the system.

A specific form of the invention is shown in Figs. 2, 3 and 4 in which upper spherical tanks 30 and 31 are supported by tubular columns 32, 33, 34 and 35 above the ground 36 and above a lower spherical tank 37. The upper tank 30 is provided with an air vent 47. All of the tanks contain liquid, the liquid level in the uppermost tank 30 being designated by the reference numeral 38, that in the next uppermost tank by the reference numeral 39, and the liquid level in the lowermost tank being designated by the numeral 40. The supporting column 32 is connected to an opening 41 in the tank 30 which in turn is connected to a pipe 41a extending therefrom to a point beneath the level 38. The column 32 also connects with the lower tank 37 through an opening 42 therein, from which opening a pipe 42a extends downwardly into the liquid therein. The column 33 is connected with the interior of the tank 37 above the liquid level 40 by means of an opening 43 and is also connected to the tank 31 through an opening 44 therein. By virtue of the apparatus so far described, the pressure generated by liquid within the tank 30 and supporting column 32 is transmitted to the tank 37 and thence through air in the column 33 to the tank 31. The tank 31 is provided with an open ended pipe 45a extending upwardly from beneath the

liquid level and connected to an outlet 45 opening into supporting column 34 which, in turn, is connected to an outlet 46 for the pressure system. Outlet 46 may be used to fill the tanks at the start. The water supply in the tank 31 may be replenished by a supply line within the column 35 and may be pumped thereinto by means of a high pressure pump. The liquid within the tanks 30 and 31 is employed only in the pressure generating system and does not under normal operation reach the tank 31 or the outlet 46.

In the specific example of the invention shown in Fig. 2, the pressure generated at the outlet 46 is substantially equal to the pressure which would be generated by a single tank elevated to a position approximately double the height of the mean elevation of tanks 30 and 31.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. A water supply system comprising three sealed tanks having their centers lying in a single vertical plane and each of said tanks containing water, a plurality of columns for supporting the tanks, one of said columns acting as a riser and connecting the water in the lowest tank with the water in one of the upper tanks, another of said columns connecting the space above the water in the lowest tank with the other upper tank, and a third of said columns acting as a riser for said other upper tank.

2. A water supply system comprising three sealed spherical tanks having their centers lying in a single vertical plane and each of said tanks containing water, a plurality of tubular columns for supporting the tanks, one of said columns being provided with a passage connected at one end to one of the upper tanks and its other end to the lower tank said connection being below the level of water in each of said tanks, another of said columns having a passage connected at one

10

end to the space above the water in the lowest tank and connected at the other end to the other upper tank, and a third of said columns acting as a riser for said other upper tank.

5 3. A water supply system comprising three tanks having their centers lying in a single vertical plane and each of said tanks containing water, a plurality of columns for supporting the tanks, one of the upper tanks being open to atmosphere and the other tanks being sealed, one of said columns acting as a riser and connecting the water in the upper open tank to the lowest tank below the water level therein, another of said columns connecting the space above the water in the lowest tank with the sealed upper tank, and a third of said columns acting as a riser for said sealed upper tank.

4. A water supply system comprising three spherical tanks having their centers lying in a single vertical plane and each of said tanks containing water, one upper tank being open to atmosphere and the other tanks being sealed, a plurality of tubular columns for supporting the tanks, one of said columns being provided with a passage connected at one end to the upper open tank and at its other end to the lower tank said connection being below the level of water in each of said tanks, another of said columns having a passage connected at one end to the space above the water in the lowest tank and connected at the other end to the sealed upper tank, and a third of said columns acting as a riser for said sealed upper tank.
